George Codish, New York, N. Y., assignor to Craft Sole Sales Company, Paterson, N. J., a partnership

Application July 17, 1945, Serial No. 120,760

Term of patent 3½ years

(Cl. D7—7)

To all whom it may concern:

Be it known that I, George Codish, a citizen of the United States, residing in New York city, county of Bronx, State of New York, have invented a new, original, and ornamental Design for a Woman's Shoe or the like, of which the following is a specification, reference being had to the accompanying drawing, forming a part thereof.

Fig. 1 is a front view of a woman's shoe showing my new design; and

Fig. 2 is a side view thereof.

I claim:

The ornamental design for a woman's shoe or the like, as shown.

GEORGE CODISH.
